UNITED STATES PATENT OFFICE

162,260

LAMP

Walter M. Thompson, Jr., East Providence, R. I.

Application May 1, 1950, Serial No. 9,611

Term of patent 14 years

(Cl. D48—20)

To all whom it may concern:

Be it known that I, Walter M. Thompson, Jr., a citizen of the United States, residing at East Providence, in the county of Providence and State of Rhode Island, have invented a new, original, and ornamental Design for a Lamp, of which the following is a specification, reference being had to the accompanying drawing, forming part thereof.

The single drawing figure is a front elevational view of a lamp showing my new design.

I claim:

The ornamental design for a lamp, as shown.

WALTER M. THOMPSON, JR.
